UNITED STATES PATENT OFFICE.

MOSES PENTLAND, OF NEWBEREY, MICHIGAN.

RAIL JOINT.

Application filed August 1, 1925. Serial No. 47,520.

This invention relates to improvements in rail joints, and has for its principal object to provide a means for connecting the abutting ends of a pair of aligned rails together in such a manner as to prevent the hammering, or battering of the ends of the rails as well as eliminating the usual clicking noises incident to the wheels of a car passing over the abutting ends of the rails.

10 A further object is to provide a rail joint of the above mentioned character wherein the same includes a base plate for supporting the rails in aligning relation, and which will prevent the lateral creeping of the rails.

15 A further object is to provide a rail joint of the above mentioned character, which is simple in construction, inexpensive, strong and durable and further well adapted to the purpose for which it is designed.

20 Other objects and advantages of the invention will become apparent during the course of the following description taken in connection with the accompanying drawing.

In the accompanying drawing forming a part of this application and in which like numerals designate like parts throughout the same:

25 Figure 1 is a side elevation of the outer plate, and the base plate showing the same secured with respect to the abutting ends of a pair of rails.

Figure 2 is a top plan view.

30 Figure 3 is a sectional view taken approximately on line 3—3 of Figure 2, and

35 Figure 4 is a detail perspective view of the outer fish plate.

In the drawing, wherein for the purpose of illustration is shown the preferred embodiment of my invention, the numerals 1 and 2 designate the end portions of a pair of aligned abutting rails of the usual construction. For the purpose of securing the rails on the usual cross ties in proper aligning relation, and to further prevent the lateral 40 creeping of the rails, I provide the base plate designated by the numeral 3, the same being provided at its longitudinal side edges with the upstanding flanges 4 and 5 respectively. The upper portion of the flange 5

50 is disposed inwardly as at 6, and extends over the inner longitudinal side edge of the base of the rails 1 and 2 in the manner as more clearly illustrated in Figures 2 and 3. The base plate 3 is of a greater width than the base of the rails so as to provide a space 7 between the outer longitudinal side edge

of the base of the rails, and the adjacent side of the longitudinally extending flange 4 which is formed on the outer longitudinal side edge of the base plate. Suitable notches 60 or cut out portions 8 are formed in each of the flanges for receiving the usual fastening spikes which are to be driven into the ties (not shown) whereby the base plate is secured rigidly on the tie. 65

An inner fish plate 9 of any well known construction extends longitudinally adjacent the inner side of the webs of the abutting rails 1 and 2, the upper edge of the fish plate 9 being disposed below the tread portion or ball of the rail while the lower edge rests on the base portion of the rail in the manner clearly illustrated in Figure 3.

The outer fish plate is designated generally by the numeral 10, and the same is adapted 75 to be disposed adjacent the outer sides of the webs of the aligned abutting rails 1 and 2 in the manner as clearly illustrated in the drawing. Extending laterally, and slightly downwardly from the lower portion of the 80 outer fish plate 10 is the base flange 11, the same being adapted to engage the base of the abutting rails. A downwardly extending tongue 12 is formed on the outer longitudinal edge of the base flange 11, and this 85 tongue is adapted to be received within the space 7, the inner side of the tongue engaging the outer edge of the base flanges of the abutting rails, while the outer side of the tongue engages the inner side of the 90 upstanding outer flange 4 formed on the base plate 3.

The intermediate portion of the outer fish plate 10 is thickened on the outer side as indicated at 13, the end portions gradually decreasing in thickness from its center toward the end as indicated at 14. The upper portion of the thickened portion 13 extends above the upper edge of the fish plate, and provides the longitudinally extending 100 tread portion 15, the ends of which gradually taper downwardly toward the outer edge of the upper face of the outer fish plate 10, as indicated at 16. This construction is more clearly illustrated in Figure 4 of the drawing. 105

The outer fish plate 10 is provided with the openings 17 which register with similar openings formed in the inner fish plate whereby the fastening bolts 18 extend therethrough and through registering openings provided therefor in the web portions of 110

the abutting rails, and suitable lock nuts 19 are threaded on the threaded ends of the bolts, whereby the fish plates are secured on opposite sides of the webs of the rails, the 5 upper edge of the outer fish plate 10 engaging the under side of the tread portion 2 of the abutting rails while the tread portion 15 of the thickened intermediate portion 13 fits against the outer edges of the tread portions of the abutting rails, and the upper face of the tread portion is flush with the upper face or ball portion of the abutting rails. In this manner, the point at which the rails 1 and 2 abut will be of relatively 10 great thickness or width, and it is obvious that when the wheels of a train pass over the joints, the tread portion 15 will tend to relieve the strain placed on the tread portions of the abutting rails, and will furthermore 15 prevent the hammering or battering of the ends of the rails as well as prevent the usual clicking noises incident to the wheels of a car passing over the abutting ends of a pair of aligned rails.

20 A rail joint of the above mentioned character may be readily and easily installed in use with rails of the conventional construction, and the provision of the base plate will prevent the rails from being moved out of alignment, as well as eliminating the lateral creeping of the rails, thus preventing any serious accidents occurring due to the rails being moved out of alignment.

25 The simplicity in which my improved rail joint is constructed renders the same very inexpensive, yet strong and durable, and when installed will at all times be positive in carrying out the purposes for which it is designed.

30 While I have shown the preferred embodiment of the invention, it is to be understood that minor changes in the size, shape, and

arrangement of parts may be resorted to without departing from the spirit of the invention and the scope of the appended 45 claim.

Having thus described the invention, what I claim is:—

A rail joint comprising in combination, a pair of aligned abutting rails, a base plate 50 therefor, said base plate being of greater width than the bases of the aforementioned rails, upstanding flanges at the sides of the base plate, the inner flange being of a greater height than the outer flange, said inner 55 flange abutting the longitudinal edges of the rail bases, the upper portion of said flange being bent and disposed inwardly over the inner longitudinal edge portions of the bases of the abutting rails, the outer side 60 flange of said base plate being spaced from the outer side edges of the rail bases, and inner and outer fish plates secured on the opposite sides of the web portions of the abutting rails, a base flange formed on the 65 lower portion of the outer plate and extending over the outer base flanges of the abutting rails, and a depending tongue formed on the outer edge of the aforementioned base flange, said tongue extending downwardly in the space formed between the outer longitudinal edges of the abutting rails and the outer side flange of the base plate, the bottom edge of the depending 70 tongue engaging the upper face of the base 75 plate, the inner side of the depending tongue engaging the outer longitudinal edges of the rail bases, the outer side of the depending tongue being in engagement with the inner side of the upstanding flange 80 formed at the outer edge of the base plate.

In testimony whereof I affix my signature.

MOSES PENTLAND.
